(57) **CLAIM**

The ornamental design for a wall mounted hanger, as shown and described.

DESCRIPTION

FIG. 1 is a perspective view showing a new design for a wall mounted hanger;

FIG. 2 is a front view thereof;

FIG. 3 is a top view thereof;

FIG. 4 is a right side view thereof;

FIG. 5 is a left side view thereof;

FIG. 6 is a bottom view thereof; and,

FIG. 7 is a rear view thereof.

The portions of the wall mounted hanger shown in broken lines in FIGS. 1 and 2 form no part of the claimed design.

1 Claim, 3 Drawing Sheets
